UNITED STATES PATENT OFFICE.

CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK.

TRAIN CONTROL.

Application filed January 3, 1922. Serial No. 526,556.

This invention relates to cab signal or train control systems, and particularly to means for transmitting a communicating influence from the trackway to a moving vehicle.

In cab signal and train control systems, it is necessary to communicate control influences from the trackway to a moving train under dangerous traffic conditions, such as an occupied block or crossing, open siding, or the like; such communicating influences being received on the vehicle by suitable mechanism, which will automatically slow down or stop the train or impose some other form of control. It is considered desirable to establish such communication between the trackway and moving vehicles inductively, rather than by physical contact between mechanism on the vehicle and devices along the track. On account of the clearances required between devices on the vehicle with respect to the track and devices on the track with respect to rolling stock of all kinds, including snow "flangers", such inductive communication must take place through a relatively large air gap when the track elements are between the track rails, and this air gap will reduce the magnitude of such communicating influences considerably.

Also, in one type of system to which this invention is more particularly adaptable, the stopping influence is produced on the car on account of the magnetic nature of the track element; and since the track rails at switches and crossings, and like magnetic bodies along the track, will tend to produce an effect upon the car apparatus similar to that of the track element, there is a difficulty encountered in this type of system, conveniently termed "rail interference", that necessitates special provision to distinguish between the effects of the regular track element in its active stopping condition and the effect of track rails, and the like. One remedy for this difficulty is to provide a construction of track element that is capable of producing a magnetic effect quite different from any organization of track rails or other magnetic bodies ordinarily encountered along the track, so that the car apparatus is able to effectively differentiate, so to speak, between the magnetic loop or partial circuit afforded by the track element and that afforded by the track rails.

With the above and other considerations in mind, the principal object and purpose of the present invention is to accentuate the influence in an inductive communicating system of this kind, without expensive addition or duplication of parts, by superimposing a plurality of successive influences upon the same car-carried apparatus in a manner whereby the effect of such influences will be cumulative, and will occur in a relation not likely to be produced by track rails or other magnetic bodies along the track.

Other objects and purposes of the invention will appear as the description progresses.

In describing the various embodiments of my invention, reference will be made to the accompanying drawings, in which:

Fig. 1 shows diagrammatically one arrangement of trackway circuits which may be used in connection with the influence transmitting means embodying the present invention;

Fig. 2 is a diagrammatic perspective view showing how the track and car elements are mounted relatively to the vehicle and trackway;

Fig. 3 is a circuit diagram of one form of train control system employing the present invention;

Fig. 4 shows graphs or curves of the voltages induced due to a change of flux in the several magnetic circuits of the car-carried element;

Fig. 4A shows a curve of the resultant voltage due to the voltages graphically illustrated in Fig. 4;

Fig. 5 is a circuit diagram of a modified form of train control embodying the present invention; and

Fig. 6 is a plan view of the car element illustrated in Figs. 3 and 5.

In the embodiment of the invention illustrated, the transmission of the desired controlling influences is produced by track elements which are governed in accordance with traffic conditions. Various arrangements of trackway circuits suitable for this purpose may be employed, and it is to be understood that the arrangement shown in Fig. 1 is merely illustrative. Referring to Fig. 1, the track rails 1 of the railroad track are divided by insulating joints 2 into blocks in the usual way, one block I with the adjacent ends

of two other blocks H and J being shown. The parts and circuits associated with the various blocks are the same, and for convenience will be given like reference characters with distinctive exponents. Each of the blocks is provided with a track battery 3 and a track relay 4, the same as in the ordinary block signaling systems. My invention may be used with or without the usual fixed signals, depending upon the type of train control apparatus; and I have illustrated such fixed signals S conventionally without attempting to illustrate their well-known control circuits and devices.

18 The trackway device of my invention in general comprises a pair of magnetic yokes or cores and associated coils, which are adapted to influence by electro-magnetic induction a cooperating element on a passing vehicle. In the construction illustrated, the trackway device comprises a pair of track elements T and U, each comprising a U-shaped core 5, preferably laminated, and provided with enlarged pole pieces 6. Each core 5 has a coil 7 on each of its legs; and these coils are wound and connected in series so that the electro-motive-forces generated in these coils 7 by a change of flux through the core 5 are cumulative or additive. One 30 of the legs of the U-shaped core 5 of each track element is preferably slightly longer than the other (see Fig. 3), for purposes to be explained hereinafter. These track elements T and U are mounted substantially parallel to each other and crosswise of the track in a manner to bring the adjacent pole pieces 6 of the longer legs substantially in the center of the track as illustrated.

These trackway elements T and U produce and transmit controlling influences or impulses to a passing train at one or more control points in each block, in accordance with traffic conditions in the next block in advance alone, or both the next block in advance and the corresponding block, depending upon the type of train control apparatus employed. In the trackway equipment illustrated in Fig. 1, a pair of trackway elements T and U are located at the entrance to each block, a short distance in the rear of insulated joints 2, the normal direction of traffic being from left to right as indicated by the arrow. The coils 7 of each of the trackway elements T and U are connected in series in separate normally closed circuits including the front contacts 8 and 9, respectively, of a line relay 10. In the arrangement illustrated, the control circuit for the line relay 10 includes a front contact 11 of the track relay 4 of the corresponding block, and a front contact 12¹ of the track relay 4¹ of the next block in advance, so that the coils 7 of the trackway elements T and U at the entrance to each block are in a closed circuit of preferably

low resistance under clear traffic conditions, but are open-circuited when either the corresponding block or the next block in advance is occupied.

The car element L for cooperating with the track elements T and U (Figs. 2, 3 and 6), comprises a yoke Y having three vertically disposed legs 13, 14 and 15, each having an enlarged pole piece. This yoke, which is preferably made up of soft iron laminations, is supported in a suitable manner (not shown) from the locomotive or other vehicle and is so positioned on this vehicle that two of its legs, such as 13 and 14 which are spaced apart the same distance as the legs of a track element, will pass directly over the two legs of the track element T, while the legs 14 and 15 will pass directly over the two legs of the other track element U. The manner in which the car element L may be supported will vary according to the type of locomotive or car, and it has not been attempted to show any particular construction for this purpose. In the case of the ordinary locomotive a convenient place for the car element L is found in front of the pony truck; and in all cases it is desirable to keep the pole pieces of the car element as far away from any iron parts of the engine frame as possible. The car element L with its coils will in practice be inclosed and protected in a casing of suitable non-magnetic material.

The car element L and the track elements T and U are disposed so as to make the air gap between their pole pieces as small as possible, consistent with the roadway and equipment clearances on the particular railroad. On certain railroads the flangers of the snow plow extend considerably below the top edge of the rail between the rails of the track, but need not extend necessarily along the entire distance between the rails, because the middle portion of the space between the rails need not be plowed out lower than the top edge of the rails. This may be done by notching out the middle part of the flanger; and for systems of this kind those legs of the track elements disposed midway between the rails may extend up to substantially the top of the rails as illustrated in Fig. 3, thereby improving the air gap to the extent permissible under practical working conditions on such roads.

On the two outside legs 13 and 15 of the car element L, shown in Fig. 3, are two coils 16 and 17 conveniently termed primary coils, which are wound with the same number of turns, and are connected together in an energized circuit, so that they will create opposing magneto-motive-forces tending to send flux in the same direction in the back yoke Y and outside legs 13 and 15, and in the opposite direction in the middle leg 14. Putting it another way, if the coil 16

makes a north pole at its pole piece, the other coil 17 makes a south pole at its pole piece, and the magneto-motive-force exerted in the middle leg 14 by one of these coils 5 will be counteracted by the magneto-motive-force exerted by the other coil.

Since the impulse transmitting means embodying the present invention may be used to control any suitable type of brake 10 or train control apparatus; and since the particular form of this apparatus forms no part of the present invention, I have illustrated conventionally a simple train control device in the form of an electro-pneumatic valve E. P. V., which may be used to vent the train pipe to apply the brakes directly, or govern the operation of any form of speed regulating or brake controlling mechanism. The electro-pneumatic 15 valve E. P. V. is normally energized, and is set into operation when deenergized. While the E. P. V. may be made so as to be directly responsive to the inductive control influences transmitted by magnetic 20 cooperation of the car-carried and track-way elements, I consider it preferable in most cases to employ a control relay R for governing said E. P. V. This relay R is of course constructed to have operating 25 characteristics conforming with its use; but since these features form no part of the present invention, this relay has been illustrated conventionally.

While the control relay R may also be 30 made directly responsive to the inductive control influence, it is considered preferable to employ an amplifying device responding to the influence for governing said relay, in order that the working current for said 35 relay may be larger and the relay made more substantial and reliable in construction. For this purpose an amplifier of the thermionic or vacuum type, commonly known as an audion, is employed. This 40 audion, being well-known in the electrical art, is illustrated conventionally and comprises a filament F, a grid G and a plate P.

This audion and the other parts are connected up with suitable sources of current 45 illustrated as batteries A, B, and C. Generally speaking, the secondary coil 18 of the car element L, the audion, and the control relay R are so connected in the system that the front contact 19 of the relay will open 50 as the car passes over the pair of track elements T and U in their active stopping condition. The electrical connections of 55 these devices may take various forms and the particular arrangements shown are merely typical and have been illustrated so that the operation of the communicating device may be explained.

Referring to Fig. 3, the filament F of the audion is heated by a battery A. The 60 grid G is connected in circuit with the sec-

ondary coil 18 and the battery B, so that a positive potential with respect to the negative end or average potential of the filament is normally maintained. This grid circuit may be traced as follows:—beginning at the positive terminal of the battery B, wire 27, secondary coil 18, wire 28, grid G to the filament of the audion, back to the negative terminal of the battery B. This permits current to flow in the plate 70 circuit through the relay R, as follows:—beginning at the positive terminal of the battery C, wire 29, front contact 19 of the control relay R, wire 30, wire 31, winding of the control relay R, wire 32, plate 75 P of the audion to the filament F, and back to the negative terminal of the battery C. The primary coils 16 and 17 are connected in series with the E. P. V. and are energized by the batteries B and C in 80 a circuit which may be traced as follows:—beginning at the positive side of the battery C, wire 29, front contact 19 of control relay R, wire 30, wire 33, contact 21 of reset switch RS, wire 34, wire of the 85 train control device E. P. V., wire 35, primary coil 17, wire 36, primary coil 16, wire 37, and back to the negative terminal of the battery C. The primary circuit is controlled by the front contact 19 of the relay 90 R, the relay R being connected in the plate circuit of the audion through the batteries B and C and through the front contact 95 19 of the relay R, thus making this relay a stick relay, which, if momentarily opened, will remain open until it is again reset. For the purpose of resetting this stick control relay R after it has been deenergized, a reset switch RS has been provided which 100 comprises a push button or double throw 105 switch blade 20 cooperating with stationary contacts 21 and 22 in a manner such that the circuit through the E. P. V. will be broken when the front contact 19 of the relay is shunted by pushing the button 23 110 of this reset switch RS. The advantage of this form of reset switch makes it impossible for the engineer to prevent the actuation of the E. P. V., by holding or fastening down the reset switch to shunt 115 the front contact 19 of the control relay R, because when the switch is operated to shunt said front contact, the circuit through the E. P. V. will be broken at the contact 21, thus effecting an automatic stop 120 or other form of control.

When the car is traveling between the track devices under normal clear traffic conditions, the relay R is energized, and in turn maintains the train control device 125 E. P. V. energized. The current in the primary coils 16 and 17 tends to send flux through the yoke Y and across the space between the outside legs 15 and 16, there being little, if any, flux passing through 130

the middle leg, because the magneto-motive forces through it are opposed, and the magnetic circuits are constructed so as to be as nearly balanced as possible.

- 5 Assume now that the car element L is passing in the direction of the arrow over a pair of track elements T and U having their coils open circuited, corresponding to dangerous traffic conditions ahead, that is, 10 when a stopping impulse should be transmitted. The first track element T under this condition presents a magnetic bridge across two legs 13 and 14 of the yoke Y, thus causing a change of flux through these legs 15 and inducing in the secondary coil 18 one cycle of voltage, as shown by the graph or curve 24 in Fig. 4, the portions of the curve above the line being taken as positive and thus adding to the voltage of the battery B, 20 whereas the portion of the curve below the line represents a negative voltage opposing the voltage of this battery.

When the car element L passes over the other track element U, a corresponding voltage will be induced in the secondary coil 18 which will be in the opposite direction to the first cycle of voltage induced, because the voltage in the second instance is due to the flux produced by the pole 15, which is of 25 opposite polarity to the pole 13 which produced the first change of flux. The distance between the track elements is properly chosen with due regard to varying conditions found in practice, so that the second 30 part or negative portion of the first curve 24 will be substantially in phase with the first part or negative portion of the second curve 25, thus inducing a resultant voltage 35 in the secondary coil as illustrated by the curve 26 in Fig. 4^A. The negative portion of the curve 26, shown in Fig. 4^A, comprises the summation of portions of the curves 40 illustrated in Fig. 4, and the middle downwardly projecting portion of this curve 45 represents a voltage double that represented by the first and last portions of this curve, which first and last portions represent the voltages of single waves. These curves are 50 only representative, and are not to be accepted as accurate for every condition. This reduction of potential on the grid G of the audion produces a magnified reduction of the plate current of the audion passing 55 through the relay R. The deenergization of the plate circuit causes the armature and front contact 19 of the control relay R to drop, thereby opening the circuit through the E. P. V.

60 The deenergization of the train control valve E. P. V. causes the train to be automatically slowed down or brought to a stop in a manner dependent upon the particular kind of train control apparatus used. To restore the relay R and reset the train control valve E. P. V., it is necessary to push the

button 23 of the reset switch, which will establish the following circuit:—beginning at the positive terminal of the battery C, wire 29, wire 38, contact 22 of the reset switch RS, wire 33, wire 31, winding of the 70 control relay R, wire 32, plate P of the audion to the filament thereof, and back to the negative side of the battery C. The completion of this circuit will energize the control relay R and close its front contact 75 19, whereupon this relay R is held up through the stick circuit heretofore traced. The reset switch 23 is preferably made accessible only from the ground, locked or sealed, or otherwise constructed so that it 80 can not be operated until appropriate measures to safeguard the train are taken.

Assume now that a car, equipped with the train control apparatus illustrated in Fig. 3 in a normal condition as shown, is moving 85 in the direction of the arrow and is approaching the entrance of the block I; and assume further that there is no train in block I or J so that the line relay 10 is energized and has its front contacts 8 and 9 90 closed, thus including the coils 7 of track elements T and U in closed circuits of low resistance. If now the car element L passes over the track elements T and U, no control influence will be transmitted. This is believed to be due to the fact that a bucking or demagnetizing current is set up in the coils 7 of the track elements T and U, due 95 to a slight increase of flux which will set up a counter-magneto-motive-force tending 100 to prevent a further increase in flux, this slight change of flux being insufficient to generate sufficient E. M. F. in the secondary coil 18 to drop the armature of the control relay R. Thus, the track elements T and U are ineffective to transmit a control influence when in their normal condition, that is, with their coils 7 in closed circuits of 105 low resistance.

Whenever the car element L passes over 110 magnetic bodies, such as switch points, crossing rails and the like, it is found that no appreciable, if any, voltage will be induced in the secondary coil 18. According to one 115 theory, this may be attributed to the fact that the shortest path for the magnetism will be through the yoke, its outside legs and the crossing rail, so that there is no change in flux through the secondary coil 18 on the middle leg 14. If the crossing rail or switch point should make an acute angle 120 with respect to the track, the rail would bridge the middle leg and one of the outside legs before it would bridge the middle leg 125 and the other outside leg, thus tending to cause an unbalancing of the opposing magneto-motive-forces in the middle leg 14, due to a difference in the reluctance of the two partial magnetic circuits through said leg occasioned by the switch point or crossing 130

rail; and such unbalancing causes a change in flux through the secondary coil 18, affecting the grid potential, and dropping relay R, with the result that a harmful and false impulse may be transmitted under unfavorable conditions.

In order to obviate the possibility of such a false influence, the outside legs 13 and 15 of the track element are preferably provided with extending pole pieces 39 and 40, preferably made up of soft iron laminations. These pole pieces, which have been shown broken away in Figs. 3 and 5 to avoid confusion, may take various forms, but are preferably of arcuate shape, as illustrated in Fig. 6. If a car element L, provided with arcuate extending pole pieces of this kind, passes over a crossing track rail making an unfavorable angle with respect to the track, changes in reluctance will take place simultaneously in the two outside legs of the car element L, the shortest path for the flux being through the yoke, outside legs, extended pole pieces and the crossing rail, so that very little, if any, change of flux will occur in the middle leg, thus inducing little, if any, voltage in the secondary coil 18 and therefore not causing a false operation of the car-carried apparatus. Or, in other words, the extended pole pieces 39 and 40 facilitate a magnetic path of low reluctance through both primary legs when a crossing rail of substantially any angle with respect to the track rails is encountered, providing a path of low reluctance which does not include the leg 14 or the secondary coil 18, that is, when the two partial magnetic circuits are simultaneously completed the resultant electro-motive-force induced in the secondary coil 18 is substantially zero.

In Fig. 5 there has been illustrated a modified form of car-carried apparatus illustrated in Fig. 3. The cooperative track devices for this embodiment of the invention are the same as shown in Figs. 1, 2 and 3. The general circuit arrangement of this embodiment of the invention is substantially the same as in Fig. 3, and like parts have been designated by the same reference characters. The main differences in structure between this modified arrangement and the embodiment of Fig. 3 is that a primary coil 16¹ on the middle leg 14 has been substituted for the primary coils 16 and 17 on legs 13 and 15, respectively; and that two secondary coils 18¹ and 18², located on the legs 13 and 15 and connected by a wire 18³, have been substituted for the single secondary coil 18. These secondary coils 18¹ and 18² are so wound and connected that the voltages induced therein due to simultaneous increase or decrease of flux from the magneto-motive-force set up by the primary coil 14 will be equal and opposite.

Although the general circuit arrangement of this particular form of my invention is very much like that shown in Fig. 3, the theory and principle of operation is believed to be quite different. Assume that the track elements T and U are in their stopping or danger condition, that is, with the coils 7 on the legs thereof open circuited, and that the car equipped as illustrated in Fig. 5, with the train control valve E. P. V. energized and with the apparatus otherwise in its normal condition as illustrated, travels past these track elements. As the car element L passes over the track element T, said track element reduces the reluctance of the magnetic path through legs 13 and 14 of yoke Y, thus inducing an E. M. F. in the secondary coil 18¹ as shown by the solid curve 24 in Fig. 4; and as the car element L passes over the track element U, a voltage is generated in the secondary coil 18² in a similar manner, as represented by the dotted curve 25 of Fig. 4.

It will be noted that the first wave of the voltage induced in the secondary coil 18¹ is positive, while the first wave induced in the secondary coil 18² is negative. This is due to the fact that these coils are wound and connected oppositely as above explained. The resultant voltage due to these two induced voltages is shown by the curve 26 in Fig. 4^A; and the secondary coils 18¹ and 18² are so connected in the grid circuit that the negative or downward wave of the voltage curve 26 opposes the voltage of the battery B, this negative voltage being of sufficient magnitude under predetermined operating conditions to buck or oppose the voltage of battery B to such an amount that the control relay R will open its front contact 19 and deenergize the train control valve E. P. V., and thereby control the train in any suitable manner as heretofore explained.

When crossing rails are encountered disposed crosswise of the track rails, no resultant voltage will be induced in the secondary or grid circuit to oppose the voltage of the battery B, because the slight voltages induced in the secondary coils 18¹ and 18² due to the change of reluctance caused by the track rails will be equal and opposite. It is apparent that crossing rails making an acute angle with the track rails will induce voltages in the secondary coils 18¹ and 18² which may, under certain adverse circumstances, not be induced simultaneously and therefore will not fully oppose each other, thereby tending to cause a false stopping control. In order to bring these voltages in time phase relation or induce them simultaneously, extended pole pieces 39 and 40, as illustrated in Fig. 6, are preferably used. These extended pole pieces 39 and 40 cause the reluctance of both magnetic paths through the secondary coils 18¹ and 18² to

be changed simultaneously as the car element L passes over such rails making an acute angle with the track rails. The effect of these extended pole pieces is similar to 5 that described in connection with the first embodiment of the invention.

This invention provides an influence communicating or transmitting means for train control systems embodying a car-carried element which receives one form of influence when approaching a track element, and another form of influence when receding from 10 a track element, and in which the approaching influence of a track element disposed in a particular relation to the car element will be in the same direction as the receding influence due to another track element disposed in a different relation to the car element, thereby forming a plurality of influences received in the proper time phase 15 relation to be cumulative. Also, the plurality of influences received from track rails disposed at an angle to the trackway are not cumulative but opposed in character.

20 With regard to the problem of rail interference characteristic of the type of influence communicating means employing an inert unenergized track element, it will be appreciated that the track element can in practice be made a much better magnetic conductor than the switch points, crossing rails, water pans, and other bodies of magnetic material ordinarily encountered along a railroad track. The track elements, however, when located between the track rails, have to be kept down below the level of the track rails at least, so as to be out of the way of the rolling stock; and if it is required to have these track elements clear of the 25 flangers of snow plows, the track elements must be kept some distance below the level of the top of the track rails. Consequently, under the practical working conditions ordinarily encountered in practice, the track rails of crossings, switch points, and the like will be closer to the car-carried element than the cores of the track elements, and will have an advantage of a smaller air gap 30 in changing the reluctance of the partial magnetic circuits of the car element.

Another factor is that the car relay R is preferably dropped by the track elements with an ample margin to take care of variations in battery voltage, changes in the air 35 gaps due to wheel wear, changes in resistance of the several coils or windings due to temperature variations, and so on; and while the track element should always cause operation of the relay under the most unfavorable 40 conditions of battery voltage, air gap, and the like, likewise the switch points or track rails of crossings should not cause operation of the relay under the most favorable conditions of air gap and the like; otherwise 45 there is a possibility of an improper or pre-

mature operation of the relay when conditions are such to favor its operation by the track elements as well as by switch points and the like.

On account of these variable factors, it 70 will be evident that the problem of rail interference resolves itself, so to speak, into the problem of making the regular track elements of the system as effective as possible when compared with the rails of crossings and switch points; and it will be evident that there is considerable difficulty in doing this where it is attempted to keep all parts of the track elements down close to the top of the ties so as to clear the flangers of 75 snow plows, many railroads apparently seriously objecting to raising the flangers at each track element. This difficulty is partially cured if, as previously explained, the snow flangers are notched or cut out for 80 a few inches in the middle of the track, where an accumulation of snow and ice is not so objectionable, so that the legs and pole pieces of the track elements may be brought up at this point approximately on 85 a level with the top of the rails, it being obvious that this expedient reduces the air gap between the car element and the track element on one side.

This specific arrangement is the one shown 90 in the accompanying drawings; but it should be understood that the invention is in no wise limited to this particular arrangement, and that the outside legs of the track elements may also come up to the level of the 100 top of the rails, or even above if the practical working conditions and the requirements of the railroad permit.

It might be added that arrangements 105 of the track elements other than that shown may be employed, the car apparatus of course being modified accordingly. For example, if desired, the track elements may be located one inside of the rail and the other outside, or both outside of the rails, disposed 110 either crosswise or lengthwise of the track so long as the relative spacing, or the points of cooperation between the car-carried and trackway partial circuits, are made in accordance with this invention, so as to produce 115 two overlapping unicyclic impulses.

From the foregoing discussion in regard 120 to the problem of rail interference, it will be appreciated that material advantages is obtained in widening the margin for a safe and reliable operation, if the influence produced between track elements is increased with respect to the similar influence that any track rail or switch point will be able to produce under like conditions of air gap, 125 battery voltage and the like.

According to this invention, this desirable end is obtained, as previously explained, by providing a combination or arrangement of 130 partial magnetic circuits of the trackway in a

spaced relation so as to produce overlapped waves, as shown in Fig. 4^A, with the result that the voltage change causing operation of the car apparatus and produced by the 5 track elements is much greater, perhaps even double, than that which can be produced by a track rail. Consequently, although the air gap between the track rail and car element is less than that between the track element and 10 said car element, the difference in the magnitude of the influences produced, respectively, by the track rail and track element results in a safe and effective operation of the relay under most unfavorable conditions 15 when the train passes an active group of track elements, while the relay is not operated under most favorable conditions by a switch point or track rail of a crossing.

It should be noted that the spacing of the 20 track elements T and U is of course made much shorter than the track gauge, so that the two rails of a crossing will not produce the successive influences necessary to obtain the same effect as the two track elements.

25 In short, in accordance with this invention, the track elements in cooperation with the car apparatus produces a distinctive and accentuated effect, specifically two overlapping unicyclic voltage curves, this effect being one 30 which can not be obtained from any arrangement or combination of track rails or other magnetic bodies ordinarily found along a railroad track. It is on account of this marked differentiation in effect that, 35 if desired, the elongated pole pieces 39 and 40 shown in Fig. 6 may be omitted where the working conditions are otherwise organized to provide the necessary margin of 40 operation between the influence of the regular track devices and the track rails.

The specific constructions and arrangements of circuits shown and described are merely illustrative of the invention, and do not exhaust the various modifications and 45 adaptations that will perform the same function and have the same mode of operation. Many changes of this character will be evident to those skilled in the art and need not be specifically shown or described. For 50 example, any well-known or suitable form of trackway circuits, or even manual control, may be employed for governing the control 55 circuits of the track elements; and while the coils 7 of these elements are shown as included in separate closed circuits, with the view of reducing the external impedance of the circuit for each pair of coils, a single 60 circuit with the two pairs of coils in series may be used to advantage in many instances. 65 Likewise, while the relay R is shown as a stick relay, it may be so connected as to open its contacts only momentarily, the desired prolongation of control being obtained by a stick relay or similar device governed by 70 said relay R. Such devices, as well as the

stick relay R shown in the particular arrangement illustrated, may, if desired, be reset or restored automatically instead of by hand. The train control apparatus itself, represented in a simple form by the 75 electro-pneumatic valve E. P. V., may take various forms, imposing the desired control or regulation of the train.

Also, it will be recognized that the various 80 adjuncts, such as cab signals, provision for reversal of the locomotive or vehicle, control for interlocking territory, and so on, may be used in connection with the system illustrated. In fact, it is appreciated that 85 this invention may be practiced by a large number of variable forms of specific apparatus and circuits, using alternating current instead of direct current, modifying the form or shape of the cores, reorganizing the 90 car circuits, and so on; and I desire to have it understood that I consider the invention to be generic in its scope and utility, and in no sense restricted to the specific embodiment illustrated and minor deviations therefrom.

What I claim is:—

1. In a train control system, the combination 95 of a plurality of trackway influence creating devices for producing successive influences each having a positive and negative value so spaced that the second influence of the first element occurs at the same time as the first influence of the second element, and car-carried apparatus including 100 an electro-responsive device having an armature associated therewith which armature responds to the accumulative effect of said influences.

2. The combination of trackway influence 105 creating means for train control and cab signal systems, comprising, a plurality of track devices each creating an approaching and receding influence, said track devices being spaced so that the receding influence of one will become effective as the approaching influence of the other becomes effective, and of car-carried apparatus including an electro-responsive device having an armature which responds to the accumulative effect of 110 said last mentioned receding and approaching influences.

3. A train control system comprising, a car-carried influence receiving device having a primary and a secondary circuit, and trackway means for producing a plurality of 115 cycles of E. M. F. in said secondary circuit in such a manner that portions of said E. M. F. are cumulative.

4. In a train control system, the combination 120 of a car-carried device for receiving control influences from the trackway, and trackway means for producing a plurality of approaching and receding influences in the car-carried devices when passing thereover, 125 said influences being so related that a re- 130

ceding influence and an approaching influence are cumulative, and means actuated by said car-carried device for restricting the speed of the train upon the reception of a cumulative influence.

5. In a train control system, the combination of a car-carried device for receiving control influences from the trackway, and a trackway influence creating means for producing a plurality of approaching and receding influences in the car-carried devices passing thereover, said influences being so displaced with respect to the position of the vehicle as it moves along the track so that a receding influence and an approaching influence are cumulative, and means actuated by said car-carried device for restricting the speed of the vehicle upon the reception of a cumulative influence.
10. In a train control system, the combination of a car-carried device for receiving control influences from the trackway, and a trackway influence creating means for producing a plurality of approaching and receding influences in the car-carried devices passing thereover, said influences being so displaced with respect to the position of the vehicle as it moves along the track so that a receding influence and an approaching influence are cumulative, and means actuated by said car-carried device for restricting the speed of the vehicle upon the reception of a cumulative influence.

15. The combination of a vehicle and a trackway on which the vehicle moves, of a car-carried element having two primary windings and a secondary winding, a direct current source of energy for energizing said primary windings to create opposite magnetic poles, and means located along the trackway for changing the flux linking said secondary winding from a maximum in one direction to a maximum in the other direction when said element passes over said trackway means.

20. In a train control system for vehicles running along a trackway, of trackway means for transmitting successive overlapping control influences, and car-carried apparatus including a car element adapted to be actuated upon the reception of overlapping influences, but ineffective to said influences when transmitted simultaneously.

25. Communicating devices for train control systems comprising, a plurality of track elements located in different paths along the trackway and spaced a distance apart to produce overlapping influences, each of said influences comprising an increasing magnetic flux followed by a decreasing magnetic flux, and car-carried apparatus including a secondary coil affected oppositely by said influences, whereby a cumulative effect will be produced upon said apparatus.

30. An automatic train control system comprising, a train control device, car-carried means for initiating said train control device including a secondary circuit, an electro-responsive device in said circuit having an armature associated therewith and a plurality of trackway devices acting cumulatively to actuate said armature when said car-carried means passes by said trackway devices.

35. Influence transmitting means for train control systems comprising, a car-carried element having a plurality of partial magnetic circuits, means associated with said partial magnetic circuits responsive to a change of

flux through either of said magnetic circuits, and a plurality of trackway devices located along the trackway in a manner to cause a cumulative influence to be transmitted by said plurality of devices when said car-carried element passes over said devices.

40. Influence transmitting apparatus for automatic train control systems comprising car-carried apparatus including an electro-responsive device connected in circuit with a secondary coil, and means including spaced trackway devices for changing the flux from a maximum in one direction to a maximum in the other direction through said secondary coil, whereby the cumulative effect of said trackway devices causes actuation of said electro-responsive device during the passage of said car-carried apparatus over said trackway devices.

45. Influence transmitting apparatus for automatic train control systems, comprising, a car-carried element of magnetic material having three legs, sources of uni-directional magneto-motive-force associated with two of said legs, and independent trackway devices for successively bridging the two air-gaps formed by the three legs of said car-carried element.

50. An automatic train control system comprising; a normally energized stick relay connected in series with a source of energy in a stick circuit, an electro-responsive device governing said relay, and means including a plurality of trackway devices for cumulatively inducing a voltage acting upon said device to cause momentary deenergization of said relay, whereby it will be permanently deenergized due to interruption of said stick circuit.

55. In an automatic train control system, the combination with car-carried apparatus including a thermionic device, and a relay controlled thereby, and of trackway means comprising a plurality of track elements adapted to cumulatively affect said device to cause deenergization of said relay when said car-carried apparatus passes by said trackway devices.

60. Influence transmitting apparatus for automatic train control systems comprising, car-carried apparatus including a secondary coil and a plurality of sources of magneto-motive-force, and trackway devices for alternately directing flux from one and then the other of said sources of magneto-motive-force through said secondary coil.

65. In an automatic train control system, the combination of car-carried apparatus comprising, a circuit including an electro-responsive device, a car element of magnetic material having two partial magnetic circuits, and means associated with said car element to cause voltages to be induced in opposite directions in said circuit when one

- of said partial magnetic circuits is magnetically bridged when the other is bridged, whereby simultaneous bridging of these partial magnetic circuits causes the voltages 5 to neutralize each other and alternate bridging of these partial magnetic circuits causes a cumulative voltage to be induced in said circuit, and of trackway elements for alternately bridging the partial magnetic circuits during the passage of the car element over the trackway elements.
17. An automatic train control system according to the preceding claim, wherein the car element is provided with extending pole 15 pieces, whereby a long magnetic body will bridge both of said partial magnetic circuits simultaneously regardless of the angular disposition of said magnetic body with respect to the trackway.
18. In a train control system the combination with a car-carried element comprising, a core having three legs, two of said legs having horizontally extending pole pieces, whereby a long magnetic body will 20 bridge both of said partial magnetic circuits simultaneously regardless of the angular disposition of said magnetic body with respect to the trackway, and trackway elements for alternately bridging one pair and 25 then another pair of said legs.
19. A train control system, comprising a car-carried influence receiving element including a core having three legs, two of said legs having pole pieces extending horizon- 30 tally on opposite sides of the third leg, 35 whereby a long magnetic body will bridge both of said partial magnetic circuits simultaneously regardless of the angular disposition of said magnetic body with respect to the trackway, and trackway elements for alternately bridging the two air-gaps formed by said three legs.
20. In an automatic train control system, the combination with a normally energized control relay on a vehicle, of means on the vehicle for reducing current in said relay comprising, a core having a receiving coil operatively connected to said relay, two opposing sources of magneto-motive-force associated with said core, both tending to send flux through said receiving coil, and trackway elements controlled in accordance with traffic conditions ahead which when active are capable of alternately reducing the reluctance between one and then the other of 50 said sources of magneto-motive-force and said receiving coil.
21. A train control system according to the preceding claim, wherein the track elements are so spaced along the trackway that the flux through said receiving coil due to one of said sources of magneto-motive-force decreases simultaneously with the increasing flux due to the other source of magneto-motive-force.

In testimony whereof I hereto affix my signature.

CHARLES S. BUSHNELL.
